TIRE

John W. Taylor, Grosse Pointe Farms, Mich., assignor to
United States Rubber Company, New York, N.Y., a
corporation of New Jersey

Filed Oct. 19, 1964, Ser. No. 82,227

Term of patent 14 years

(Cl. D90—20)

Fig. 1

*Fig. 2**Fig. 3*FIG. 1 is a perspective view of a tire embodying my new design, it being understood that the full line portion is repeated throughout the circumference of the tire, shown by means of broken lines;

FIG. 2 is an enlarged fragmentary plan view of the full line portion shown in FIG. 1;

FIG. 3 is a sectional view taken substantially on the plane indicated by line III—III of FIG. 2, but on a reduced scale.

The dominant features of my design reside in those portions shown in full lines in the drawings.

I claim:

The ornamental design for a tire, substantially as shown and described.
